UNITED STATES PATENT OFFICE

166,196

EARRING HOLDER OR SIMILAR ARTICLE

Dorothy Johns, Fort Worth, Tex., assignor of one-half to George D. Berdan, Fort Worth, Tex.

Application May 22, 1951, Serial No. 15,279

Term of patent 14 years

(Cl. D80—9)

To all whom it may concern:

Be it known that I, Dorothy Johns, a citizen of the United States, residing in Fort Worth, in the county of Tarrant, State of Texas, have invented a new, original, and ornamental Design for an Earring Holder or Similar Article, of which the following is a specification, reference being had to the accompanying drawing, forming a part thereof.

Figure 1 is a perspective view of an earring holder or similar article, showing my new design.

I claim:

The ornamental design for an earring holder or similar article, substantially as shown.

DOROTHY JOHNS.
